UNITED STATES PATENT OFFICE

2,332,503

FLUID LIFT

Sanford C. Brady, Bartlesville, Okla.

Application December 11, 1941, Serial No. 422,581

6 Claims. (Cl. 103—233)

This invention relates to an intermittent fluid lift, and it is an object of the invention to provide a device of this kind affording an efficient and economical way of lifting fluid under either self contained hole pressure or from pressure otherwise created.

It is also an object of the invention to provide a lift of this kind having means whereby is prevented, during the operation of the lift, spraying or mixing.

A still further object of the invention is to provide a device of this kind wherein means is provided to allow retrograde flow during installation or in the event there is too high a column while pressure is off.

The invention also has for an object to provide a device of this kind constituting a unit that can be independently used or can be coupled in series to allow for a multiple lift of fluid.

The invention consists in the details of construction and in the combination and arrangement of the several parts of my improved fluid lift whereby certain important advantages are attained, as will be hereinafter more fully set forth.

In order that my invention may be the better understood, I will now proceed to describe the same with reference to the accompanying drawing, wherein:

Figure 1 is a view, partly in elevation and partly in section, illustrating a fluid lift constructed in accordance with an embodiment of my invention;

Figure 2 is an enlarged sectional view taken substantially on the line 2—2 of Figure 1; and

Figure 3 is a fragmentary view, partly in section and partly in elevation, illustrating the device in multiple assembly.

As disclosed in the accompanying drawing, 1 denotes an elongated barrel of desired dimensions having both ends open and with its lower end portion restricted, as at 2. The upper end portion of the barrel 1 has threading therein a unit head H. This head H, as herein disclosed, comprises a bottom plate 3 having its peripheral portion provided with an upstanding annular wall 4 of material thickness. This plate 3 is provided with a depending annular flange 5, also of material thickness. This flange 5 is of a major diameter less than that of the head H but is concentric to the axial center of the head H.

Threading upon and surrounding the flange 5 is the upper end portion of a sleeve 6. This sleeve 6 is of a length to extend a major distance along and within the barrel 1 and is spaced

from such barrel 1 to provide therebetween an annular by-pass 7. Threading within the lower portion of this sleeve 6 is a plate 8, said plate being of such thickness as to extend below the lower end of the sleeve 6 when in applied position. The central portion of this plate 8 is provided with a relatively large opening 9 through which threads a short sleeve 10. This sleeve 10 is locked in its desired selective endwise adjustment with respect to the plate 8 by a lock nut 11 threading on the short sleeve 10 and coacting from below with the plate 8. The lower portion of this sleeve 10 carries a surrounding head 12 to facilitate the desired turning of the sleeve 10 to effect the adjustments desired.

Threading upon the lower extended portion of the plate 8 is a coupling collar 14 to which a fluid inlet member 15 is to be coupled, or to allow coupling of the sleeve 6 with the inner lower threaded portion of the head 8 of a second device when it is desired to employ the devices in multiple. The upper internally threaded portion 16 of the head H when the device is used singly or when uppermost in series allows the coupling 25 of the head H to the lower extremity of the inner pipe line 17 leading in the usual manner to the ground surface. The head H is provided with a second upper internally threaded portion 18 outwardly offset with respect to the threaded portion 16 with which is adapted to be connected the lower end portion of an outer pipe line 19 leading to the surface or to allow suitable connection by pipe with the restricted portion 2 of a device thereabove when the devices are used in multiple. The pipe lines 17 and 19 provide therebetween a passageway 20 leading to the surface with the upper end of said passageway being suitably sealed, as at 21. The inner pipe line 17 extends above the seal 21 and has in communication therewith a fluid discharge 22. The head H is provided with a port 23 in communication with the passageway 20 and with a radially disposed port 24 in the head H affording communication between the by-pass or passageway 7 to the upper end portion of a cylinder 25. This cylinder 25 has its upper end portion threading within the opening or pocket afforded by the flange 5 and has working therein a piston 26. This piston 26 is carried by the upper or inserted end portion of a tubular stem 27 which passes freely through a central opening 28 disposed through a head 29 threading into and closing the lower end of the cylinder 25. This opening 28 has threading therein from above a tubular member 30 depending from the central portion

of a seat plate 31. The stem 27 freely passes through this member 30 and threading on the tubular member 30 for coaction from below with the head 29 is a lock nut 32 whereby the seat plate 31 may be held in desired selected adjustment above the head 29.

Interposed between the head 29 and the piston 26 is an expansible member 33 of requisite tension and which operates to urge the upper end of the tubular valve stem 27 into closing engagement with the valve disk 34. This valve disk 34 is carried by an elongated shank 35 threading down through the bottom plate 3 of the head H and having a lower tapered portion 36 extending within the upper end portion of the stem 27.

The shank 35 above the plate 3 has threaded thereon a lock nut 31 for coaction from above with the plate 3 for holding the shank 35 in desired endwise adjustment. Disposed over the upper end portion of the shank 35 is a sealing cap 38 threading within a pocket or depression 39 provided in the upper surface of the plate 3. This cap 38 serves to prevent leakage around the shank 35 through the plate 3.

The bore 40 of the head H above the plate 3 is in communication with the pipe line 17 and this bore 40 is in communication with the by-pass or passageway 7 through a port 41 disposed through the plate 3 and through the flange 5 depending therefrom.

When the device as herein disclosed is used as a single unit the communication between the port 24 and the by-pass or passageway 7 is closed by a plug 42. However, when the devices are used in series this plug 42 is removed so that the gas pressure may pass down through the by-pass or passageway 7 to the port 23 of the head H of the lower device.

The stem 27 is of a length to extend at all times below the head 29 and threaded or otherwise secured to this lower extended portion of the stem 27 is a valve cap 43 which telescopically engages over the upper end portion of the sleeve 10. This cap 43 is provided in the upper part of its side wall with a pressure inlet port 44 and in its lower portion with a fluid inlet port 45 for register with a port 46 in the upper portion of the short sleeve 10. The sleeve 10 above this port 46 is closed by a head 47 and the upper surface of this head 47 is provided with a pocket 48 in the bottom portion of which is arranged a cushion 49 of rubber or other suitable material. Within the upper portion of this pocket 48 and below the lower open end of the stem 27 is a ball valve 50.

When the device is placed in a well or kindred hole, the piston 26 is held against the disk plate or valve seat 34 by the spring 33, allowing fluid to enter through the inlet member 15 and out through the port 46 into the sleeve 6. The fluid will rise upwardly within the sleeve 6 through the port 41 into the bore 40 of the head H and into the inner pipe line 17. The fluid will also pass up through the tubular member 30 into the cylinder 25 and under the piston 26. At this time the valve cap 43 is entirely above the port 46. When pressure is applied down through the passageway 20 and through the ports 23 and 24 into the cylinder 25 above the piston 26, the piston 26 will be moved downwardly allowing the pressure to pass down through the stem 27 past the valve 50 and through the port 44 into the lower portion of the sleeve 6. In this movement the upper end of the stem 27 will be open allowing the pressure to pass down into the valve cap

43 and out through the port 44 to force the fluid upwardly through the port 41 and up through the pipe line 17 for delivery through the fluid discharge 22 at the ground surface. This downward movement of the stem 27 will also cause the cap member 43 to close the port 46 so that fluid will be prevented from entering within the sleeve 6. When the fluid being lifted has reached the surface the pressure will be released from under the piston so that the greater pressure on the top of the piston 26 will push the stem 27 down into closing contact with the valve 50.

After the column of fluid has been lifted by the air or gas pressure and delivered out through the fluid discharge 22 the pressure will be released from below the piston 26 and as a result of the greater pressure on top of the piston 26 said piston will move further downward to bring the lower end of the stem 27 into closing contact with the ball valve 50 and to bring the port 45 of the cap valve into register with the port 46.

In the operation of the lift, the stem 27 will move or float between the valve disk 34 and the valve 50 and the tapered portion 36 of the shank 35 will allow volume of gas or air to keep desired pressure on flowing column. If pressure in column increases, it will move the stem 27 up on the larger part of the tapered portion 36 to restrict flow, and if the pressure decreases the stem 27 will move downwardly, allowing more gas or air to enter. If the column pressure plus pressure of the spring 33 equals the pressure on the piston 26, the stem 27 will close against the valve disk 34. When this occurs there is an equalizing of pressure between the outer or pressure string and the inner or fluid string at surface to balance the fluid height by releasing it back through the port 51.

The port 51 is disposed through the plate 3 and is normally closed by a downwardly opening valve 52. This valve 52 is maintained normally closed by an expansible member or coil spring 53 of a tension to hold the fluid but to allow the valve 52 to open when there is too high a column 45 while pressure is off or while making installation.

It is to be stated that with a 400 lb. pressure and with the member 33 being of 200 lb. tension, there will be lifted a column equal to 200 lbs. static pressure.

50 A line 54 leading from a suitable source of air or gas supply under pressure is in communication with the passageway 20 at the ground surface.

It is also believed to be apparent that when 55 a single device is employed the plug 42 is in place. However, when the devices are in multiple, the plug 42 is removed and the by-pass 7 provides desired pressure communication with the devices below. It is also to be pointed out that the pressure inlet port 44 is open at all times during the 60 operation of the lift.

From the foregoing description it is thought to be obvious that a fluid lift constructed in accordance with my invention is particularly well adapted for use by reason of the convenience and facility with which it may be assembled and operated.

I claim:

1. An apparatus for lifting liquid comprising a 70 head, a pressure line coupled to the head, a liquid carry-off line coupled to the head, a sleeve depending from the head, said head having a port affording communication between said sleeve and the carry-off line, the lower end of the sleeve being open to allow fluid to enter up into the sleeve.

a second sleeve within the first sleeve and depending from the head, said head having a second port in communication with the second sleeve, a piston working in the second sleeve, a tubular stem for the piston extending through the piston and open at both ends, said piston extending below the second sleeve, a valve member depending from the head for closing the upper open end of the tubular stem, an expansible member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, and means for closing the lower end of the tubular stem when the pressure inlet port of the cap valve and the inlet port of the third sleeve are in register.

2. An apparatus for lifting liquid comprising a head, a pressure line coupled to the head, a liquid carry-off line coupled to the head, a sleeve depending from the head, said head having a port affording communication between said sleeve and the carry-off line, the lower end of the sleeve being open to allow fluid to enter up into the sleeve, a second sleeve within the first sleeve and depending from the head, said head having a second port in communication with the second sleeve, a piston working in the second sleeve, a tubular stem for the piston extending through the piston and open at both ends, said piston extending below the second sleeve, a valve member depending from the head for closing the upper open end of the tubular stem, an expansible member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, means for closing the lower end of the tubular stem when the pressure inlet port of the cap valve and the inlet port of the third sleeve are in register, the plate closing the lower portion of the first sleeve being provided with a port therethrough, and a normally closed downwardly opening valve for said port of the plate.

3. An apparatus for lifting liquid comprising a head, a pressure line coupled to the head, a liquid carry-off line coupled to the head, a sleeve depending from the head, said head having a port affording communication between said sleeve and the carry-off line, the lower end of the sleeve being open to allow fluid to enter up into the sleeve, a second sleeve within the first sleeve and depending from the head, said head having

a second port in communication with the second sleeve, a piston working in the second sleeve, a tubular stem for the piston extending through the piston and open at both ends, said piston extending below the second sleeve, a valve member depending from the head for closing the upper open end of the tubular stem, an expansible member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, means for closing the lower end of the tubular stem when the pressure inlet port of the cap valve and the inlet port of the third sleeve are in register, the valve member depending from the head including a shank having downwardly disposed tapered portion extending within the upper portion of the tubular stem.

4. An apparatus for lifting liquid comprising a head, a pressure line coupled to the head, a liquid carry-off line coupled to the head, a sleeve depending from the head, said head having a port affording communication between said sleeve and the carry-off line, the lower end of the sleeve being open to allow fluid to enter up into the sleeve, a second sleeve within the first sleeve and depending from the head, said head having a second port in communication with the second sleeve, a piston working in the second sleeve, a tubular stem for the piston extending through the piston and open at both ends, said piston extending below the second sleeve, a valve member depending from the head for closing the upper open end of the tubular stem, an expansible member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, means for closing the lower end of the tubular stem when the pressure inlet port of the cap valve and the inlet port of the third sleeve are in register, the plate closing the lower portion of the first sleeve being provided with a port therethrough, and a normally closed downwardly opening valve for said port of the plate.

5. An apparatus for lifting liquid comprising a head, a pressure line coupled to the head, a liquid carry-off line coupled to the head, a sleeve depending from the head, said head having a port affording communication between said sleeve and the carry-off line, the lower end of the sleeve being open to allow fluid to enter up into the sleeve, a second sleeve within the first sleeve and depending from the head, said head

having a second port in communication with the second sleeve, a piston working in the second sleeve, a tubular stem for the piston extending through the piston and open at both ends, said piston extending below the second sleeve, a valve member depending from the head for closing the upper open end of the tubular stem, an expandable member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, the upper closed end of the third sleeve being provided with a pocket, and a valve member free within said pocket for closing the lower end of the tubular stem upon movement of the same toward the third sleeve.

6. An apparatus for lifting liquid comprising a head, a pressure line coupled to the head, a liquid carry-off line coupled to the head, a sleeve depending from the head, said head having a port affording communication between said sleeve and the carry-off line, the lower end of

the sleeve being open to allow fluid to enter up into the sleeve, a second sleeve within the first sleeve and depending from the head, said head having a second port in communication with the second sleeve, a piston working in the second sleeve, a tubular stem for the piston extending through the piston and open at both ends, said piston extending below the second sleeve, a valve member depending from the head for closing the upper open end of the tubular stem, an expandable member for constantly urging the piston and stem toward the valve member, a plate for closing the lower end portion of the first sleeve, a third sleeve extending up through said plate, the upper end of said third sleeve being closed and the lower end open, the side wall of the third sleeve adjacent the closed end thereof being provided with a port, a cap valve carried by the lower end portion of the tubular stem and telescopically engaging over the upper portion of the third sleeve, said cap valve being provided in its upper part with a pressure inlet port and in its lower portion with a fluid inlet port for register with the port of the third sleeve upon movement of the cap valve downwardly over the third sleeve, the upper closed end of the third valve being provided with a pocket, a valve member free within said pocket for closing the lower end of the tubular stem upon movement of the same toward the third sleeve, and a cushion within the pocket upon which the ball valve rests.

SANFORD C. BRADY.
